Joseph David INVENTOR

UNITED STATES PATENT OFFICE

JOSEPH DAVID, OF CHICAGO, ILLINOIS

GARMENT PROTECTOR

Application filed August 27, 1927. Serial No. 215,916.

My invention relates to improvements in garment protectors, and it consists in the combinations, constructions, and arrangements herein described and claimed.

5 An object of my invention is to provide a garment protector which will prevent the removal of garments from hangers by unauthorized persons.

A further object of my invention is to 10 provide a device of the type described which may be applied to hangers or racks of different types, and which is so arranged that it may receive and retain garments of various sizes or description.

15 A further object of my invention is to provide a device of the type described which is simple in construction, durable and efficient for the purpose intended.

Other objects and advantages will appear in the following specification, and the 20 novel features of the invention will be particularly pointed out in the appended claims.

My invention is illustrated in the accompanying drawings, forming part of this 25 application, in which

Figure 1 is a side elevation of my improved device as disposed in a cabinet or the like, and showing garments applied thereto,

30 Figure 2 is a section along the line 2—2 of Figure 1,

Figure 3 is a detailed transverse section of my device, and

35 Figure 4 is an enlarged detail view of a portion of my device.

In carrying out my invention, I make 40 use of a closet or cabinet 1 in which the garments 2 are normally hung. It will be readily understood that the device may be used equally as well on a display rack or the like. In the present construction, I provide a supporting rod 3 having its ends fitted in suitable bearings or sockets 4. Arranged upon this rod 3 at spaced-apart 45 points are hollow T members 5, the cross portions of which are slidably mounted upon the rod 3 but can be fixed in any desired position by means of set screws 6. Threaded into the downwardly extending stems of 50 the T members 5 are nipples 7 which are

securely held in place by set screws 8. The nipples 7 are provided at a point adjacent their lower ends with oppositely disposed openings through which extend garment supporting bars 9.

55 The bars 9 have their ends extended an equal distance upon each side of the nipples 7 and these ends are shaped to conform to the general contour of the shoulders of the garments so as to properly support the garments thereupon.

60 The improved locking feature consist of two flexible members 10 and 11 which are illustrated in the drawings in the form of chains made up by a plurality of links and 65 covered at 12 with a suitable covering, such as leather, cloth or the like. The flexible members 10 and 11 have their innermost links disposed in the nipples 7 and held in place by the central portion of the bar 9. 70 The member 10 has attached to its outer end a hook-like member 13 formed with an eye 14, whereby the shackle of a lock 15 may be passed through the eye and the outermost link of the member 11 to fasten 75 them together.

76 From the foregoing description of the various parts of the device, the operation thereof may be readily understood. The garment may first be placed upon the ends of the bar 9, as shown in Figure 2. The members 10 and 11 are then passed downwardly through the sleeves of the garment until the hook 13 passes around the cuff, see Figure 2, and the lower end of the member 11 extends through the arm. The hook member and the member 11 may be secured together by the lock 15. Should it be desired to fasten a number of garments together, as shown in Figure 1, a rod 16 is used which has a 80 relatively large eye portion 17 on one end thereof. The other end of the rod 16 is provided with a relatively small eye portion 18 which is adapted to be passed through the eye portions 14 and the lowermost links of the members 11 and receive a lock 19. The lock 19 is sufficiently large 85 to prevent the relatively small eye portion 18 from being withdrawn through the eye members 14. In this manner, all the gar- 90

ments are secured together by the use of only one lock.

It will be readily apparent from the foregoing that while I have shown the use of two members 10 and 11, the member 11 may be eliminated and the member 10 used as it is or made longer so that the hook 13 may be engaged with one of the uppermost links of this member after being passed through the sleeve of a garment. This latter method of using the device will also reduce the cost of production and can be used equally as well on different types of garments.

While I have shown and described the preferred embodiment of my invention, it will be apparent that various changes and alterations may be carried out when putting the invention into practice without departing from the spirit of the invention or the scope of the appended claims.

I claim:

1. A device of the type described comprising a supporting rod, a plurality of spaced-apart collars mounted on the rod, each of said spaced-apart collars being provided with a tubular member connected therewith, a hanger rod extending through said tubular member, a pair of chain members, each of said chain members having one end disposed within the tubular member and connected with the hanger rod, and means whereby the opposite ends of said chain members may be connected together.

2. A device of the type described comprising a supporting rod, a plurality of collars mounted on the rod, each of said collars being provided with a hollow extension, a hanger carried by the extension and extending therethrough, and a pair of chains, each of said chains having one end disposed within the extension and retained therein by the hanger, said chains being adapted for extending through the sleeves of a garment when disposed on a hanger, the opposite ends of said chains being provided with means whereby the ends may be locked together.

JOSEPH DAVID.
